FURNACE

Ralph M. Hardgrove, Bethlehem, Pa., assignor to
 Fuller Lehigh Company, Fullerton, Pa., a corporation of Delaware

Application August 13, 1930, Serial No. 475,010

14 Claims. (Cl. 122—235)

This invention relates to a furnace that is especially adapted for burning powdered fuel in which slag from the fuel is permitted to collect upon the floor of the furnace in a molten form 5 and is drawn off at intervals.

In furnaces of this character that have been used heretofore, troubles have arisen because of the slag freezing and subsequently expanding when again heated, with the result that the furnace walls are pushed outwardly. This danger 10 is sometimes caused because when the slag cools and freezes, cracks form in it which subsequently receive more molten slag that hardens therein, thus causing the slag slab to grow and expand 15 by successive heating and cooling.

By the present invention, the danger of the walls of the furnace being forced outwardly is obviated by so shaping the floor that the slag that collects upon the floor has a thin edge that 20 would be crushed before thrusting the furnace walls out. The floor is shaped so as to have sloping valleys in which the slag collects.

The invention will be understood from the description in connection with the accompanying 25 drawings, in which Fig. 1 is a vertical section through an illustrative embodiment of the invention; Fig. 2 is a section along the line 2—2 of Fig. 1, and Fig. 3 is a horizontal section through the furnace along the line 3—3 of Fig. 1.

30 In the drawings, reference character 1 indicates a furnace that is provided with one or more fuel burners 2 in the front wall thereof. The front and rear walls of the furnace are provided with vertically disposed water tubes 3 and the 35 side walls of the furnace are provided with vertically disposed water tubes 4. The tubes 3 and 4 are lined with tile or the well-known Bailey blocks to form continuous walls. The lower ends of the tubes 3 and 4 extend straight downwardly 40 into lower horizontal headers 6 and the upper ends of these tubes are bent outwardly and extend into horizontally disposed headers 7. Recirculating tubes 8 connect the headers 6 and 7 outside of the furnace walls.

45 Tubes 9 extend from the water space of the steam and water drum 10 of the boiler that is located above the furnace, to the lower headers 6 and tubes 11 extend from the upper headers 7 to the steam space of the steam and water drum 10. 50 A lower header 12 comprising at least two sections in its longitudinal dimension and here shown as being of zigzag shape is located on one side of the furnace near the bottom thereof, and a similar header 13 is located on the other side 55 of the furnace at a slightly higher elevation than

the header 12. Tubes 14 extend from the water space of the steam and water drum 10 to the lowest portions of the header 12 and tubes 15 extend from the highest portions of the header 13 to the steam space of the steam and water drum 10. 5 A row of straight, parallel inclined floor tubes 16 extends across the lower portion of the furnace from the header 12 to the header 13 in such a manner as to form a plurality of inclined valleys along the floor of the furnace, the tubes 16 passing between the tubes 3 in the furnace walls. The floor tubes 16 comprise groups of sloping parallel tubes, each group lying in a plane intersecting that in which an adjacent group lies and the headers have a section in the 10 plane of each group of tubes to which the members of that group are connected. A layer of tile or Bailey blocks 17 is placed upon the tubes 16 to provide a continuous floor for the furnace. Slag tap holes 18 are provided through the front 15 wall of the furnace at the lower ends of the valleys formed by the floor of the furnace. Slag 19 is shown collected in the lowest portions of the valleys on the floor of the furnace with the edges and sides of the layers thinned out as indicated 20 most clearly in Figs. 1 and 2 of the drawings.

The highest elevation of the floor between the side walls of the furnace is indicated by the sloping line 20 extending through the middle of the furnace and the lowest portions of the valleys 25 are indicated by the lines 21.

The side walls of the furnace are cooled by water passing from the water space of the steam and water drum 10 through the tubes 9 into the headers 6, thence upwardly through the tubes 3 and 4 into the headers 7 and tubes 11 into the drum 10. Recirculating water also passes from the headers 7 into the headers 6. The fluid that passes upwardly through the tubes 11 is steam 35 for the most part.

The floor of the furnace is cooled by water passing from the water space of the steam and water drum 10 through the tubes 14 into the header 12, thence through the tubes 16 to the header 13 from which steam or a mixture of steam and water passes through the tubes 15 to the steam space of the steam and water drum 10.

It has been found that even if the floor of the furnace is not liquid tight at the beginning, the molten slag from the fuel freezes when it comes in contact with the floor and fills up the crevices, so that a liquid-tight floor as well as liquid-tight joints between the edges of the floor and the 40 walls of the furnace can be maintained.

I claim:

1. In a furnace, a slag tight floor for retaining molten slag, contiguous groups of sloping parallel tubes in said floor, each group lying in a plane intersecting that in which another group lies, and a header to which said tubes are connected, the header comprising a plurality of sections in its longitudinal dimension, each section lying in the plane of one group of tubes, said contiguous groups providing uniform cooling of the floor from wall to wall. 5
2. In a furnace, a slag tight floor for retaining molten slag, contiguous groups of sloping parallel tubes in said floor, each group lying in a plane intersecting that in which an adjacent group lies, and a zigzag header to which the tubes are connected, said header having a section in the plane of each group of tubes, said contiguous groups providing uniform cooling of the floor from wall to wall. 10
3. In a furnace for burning a slag forming fuel, a slag retaining sloping floor holding a body of molten slag comprising contiguous groups of longitudinally inclined tubes, each group lying in a plane intersecting that in which an adjacent group lies and parallel to the intersection, said contiguous groups providing uniform cooling of the floor from wall to wall. 15
4. In a furnace for burning a slag forming fuel, a slag retaining sloping floor holding a body of molten slag comprising contiguous groups of sloping tubes, each group lying in a plane intersecting that in which an adjacent group lies and parallel to the intersection, and a slag tap opening adjacent the lower end of the intersection, said contiguous groups providing uniform cooling of the floor from wall to wall. 20
5. In a furnace for burning a slag-forming fuel, a furnace bottom including closely arranged cooling tubes and constructed to retain molten slag, said tubes being divided into a plurality of groups extending transversely from wall to wall of said furnace and arranged in intersecting planes with the line of intersection of said planes extending parallel to said tubes, said groups being completely coextensive with the bottom area supporting the molten slag, and means for supplying cooling fluid to said tubes. 25
6. In a furnace for burning a slag-forming fuel, a furnace bottom including closely arranged inclined cooling tubes and constructed to retain molten slag, means for supplying cooling fluid to the tubes, said tubes extending in single lengths from wall to wall of said furnace and being divided into a plurality of groups arranged in planes intersecting at an obtuse angle forming a depression collecting molten slag, and a slag tap opening from said depression. 30
7. In a furnace for burning a slag-forming fuel, a furnace bottom constructed to retain molten slag and arranged with a plurality of valleys thereon, a plurality of horizontally inclined water cooling tubes constructed to support the floor, said tubes having their longitudinal axes substantially parallel to the axes of said valleys. 35
8. In a furnace for burning a slag-forming fuel, a furnace bottom constructed to retain molten slag and arranged with a plurality of valleys thereon, a plurality of horizontally inclined water cooling tubes adapted to support the floor, said tubes having their longitudinal axes substantially parallel to the axes of said valleys. 40
- tubes having their longitudinal axes substantially parallel to the axes of said valleys, upright water cooled walls adjacent said floor, said walls being formed with slag tap openings at the lower ends of said valleys. 45
9. In a furnace for burning a slag-forming fuel, a furnace bottom constructed to retain molten slag, said furnace bottom comprising contiguous groups of inclined spaced water cooling tubes arranged in a plurality of planes intersecting along a line extending longitudinally of said tubes, said groups being completely coextensive with the bottom area supporting the molten slag. 50
10. In a furnace for burning a slag-forming fuel, a furnace bottom constructed to retain molten slag, said furnace bottom comprising contiguous groups of inclined spaced water cooling tubes arranged in a plurality of planes intersecting along a line extending longitudinally of said tubes, and being completely coextensive with the area supporting the molten slag, an inclined header connected to the upper ends of each group of said tubes, and discharge connections from said headers near the high points thereof. 55
11. In a furnace for burning a slag-forming fuel, a furnace bottom constructed to retain molten slag, said furnace bottom comprising contiguous groups of inclined spaced cooling tubes arranged in a plurality of intersecting planes and closure elements for the tube spaces forming an inclined valley extending longitudinally of said tubes, said groups being completely coextensive with the bottom area supporting the molten slag, upright furnace walls comprising cooling tubes adjacent said floor at the lower end of said valley, said wall being formed with a slag tap opening. 60
12. In a boiler furnace for burning a slag-forming fuel, a steam boiler, four bottom supported upwardly extending furnace side walls comprising spaced tubes connected at their ends to headers and heat resisting elements closing the spaces between the tubes, headers connected to said tubes at their upper and lower ends, means connecting said headers into the circulation of the boiler, a furnace bottom constructed to retain a pool of molten slag and including horizontally inclined tubes extending across the furnace and passing between the tubes of two opposite side walls in a single length, headers connected to the upper and lower ends of said inclined tubes, and means connecting said last mentioned headers into the circulation of the boiler independent of means connecting the first mentioned headers to the boiler. 65
13. In a furnace, a floor, wall tubes on all sides of the furnace chamber surrounding and defining the limits of said floor, circulation systems for passing a cooling fluid through said wall tubes, tubes in said floor, and a separate circulation system for passing cooling fluid through said floor tubes. 70
14. In a furnace, a floor, wall tubes on all sides of the furnace chamber surrounding and defining the limits of said floor, circulation systems for passing a cooling fluid through said wall tubes, sloping tubes in said floor, and a separate circulation system for passing cooling fluid upwardly through said floor tubes. 75
